Harry Golden, New York, N. Y.

Application April 8, 1953, Serial No. 24,407

Term of patent 7 years

(Cl. D72—1)

To all whom it may concern:

Be it known that I, Harry Golden, a citizen of the United States of America, residing at New York, county of New York, and State of New York, have invented a new, original, and ornamental Design for a Combination Handlebar Grip and Bell for Bicycles, of which the following is a specification, reference being had to the accompanying drawing, forming a part thereof.

Figure 1 is a side elevation of a combination handlebar grip and bell for bicycles, embodying my new design.

Figure 2 is a front elevational view thereof, and

Figure 3 is a rear elevational view of the same.

I claim:

The ornamental design for combination handlebar grip and bell for bicycles, as shown.

HARRY GOLDEN.
